SMALL-PUNCH DIE CONSTRUCTION

Moses D. Heyman, Woodmere, N. Y.

Application May 22, 1952, Serial No. 289,350

2 Claims. (Cl. 164—86)

This invention relates to punch and die construction and, while the same is applicable to die sets generally, it is more particularly adapted for application to die sets in which the punch elements are so small and, therefore, fragile, that their breakage, for one reason or another, is quite frequent.

In punched out relatively small non-metallic parts having one or more perforations therein, the perforations are produced by punch elements set as inserts into the die punch, said elements cooperating with a die, in the conventional manner, to pierce through a sheet or strip of material. The perforations may have various shapes and may be small, frequently in the nature of $\frac{1}{32}$ " in diameter or width. For instance, in the production of mica bridge pieces, such as used in electronic tubes, the punch of the die set used to produce said pieces may mount as many as a dozen or more small punch elements, all within a half inch or smaller circle and some of these elements may be as small or smaller than the size above indicated. It will be realized, therefore, that such small-sectioned elements are subject to frequent breakage.

The present invention has for its primary object to provide novel and improved means for immediately detecting breakage of a punch element of a die set to, thereby, obviate loss attending production of faulty parts. When such breakage of a punch is not immediately discovered, many thousands of parts may be produced with one or more perforations missing therefrom and the same must be scrapped as being faulty.

Since die sets producing such small parts are relatively small and, it being difficult and time-consuming to inspect the punch elements before each operation of the press that mounts the die set, visual detection is economically unfeasible. Another object of the invention, therefore, is to provide means automatically stopping or stalling the press should one or more of the punch elements be broken or should one or more of them be improperly seated in the punch. Thus, upon such abnormal condition, the present means will immediately stop operation of the press and the operation can be restored only when the abnormal condition is corrected.

Another object of the invention is to provide an electric circuit that controls the operation of the press and to include all of the punch elements in series in said circuit so that abnormal removal of any one such element from the circuit will open the same in the manner of a switch and stop the operation of the press.

The foregoing and other objects, features and advantages of the invention will become more clearly evident as the following description progresses, said description having basis on the preferred but exemplary form of the invention illustrated in the accompanying drawing.

In the drawing:

Fig. 1 is a side elevational view of a punch press showing a die set mounted thereon and provided with the present novel means connected to said die set for controlling the operation of the press.

2

Fig. 2 is a greatly enlarged vertical sectional view of the die set shown in Fig. 1.

Fig. 3 is a plan view of the die of said die set.

In the drawing, Fig. 1 shows a generally conventional one-revolution punch press that comprises a frame 5 having a bed 6 and mounting a ram 7 movable toward and from said bed by crank or similar mechanism 8. Said mechanism is driven from a shaft 9 by a motor 10 connected to drive a flywheel 11 on said shaft. While not shown, a conventional one-revolution clutch operatively connects shaft 9 and flywheel 11. A die set 12, comprising a die 13 mounted on bed 6 and a punch 14 carried by ram 7, is shown in typical position in the press to punch out pieces from a work strip 15 as the same is conventionally intermittently fed across the upper face of die 13. The die set may be of the compound or of the progressive type, the latter being shown. Any reciprocating press may be substituted for the conventional press above described.

For a clearer understanding of the present novel improvements, the conventional parts of the two-stage progressive die set that is illustrated will be first described.

The die 13 comprises a metal base block 16 that is adapted to be firmly secured to press bed 6 and, according to the disposition, number and size of the perforations in a piece 21 to be punched out of strip 15, said die is provided with shear perforations 17 at its first stage and with a shear perforation 18 at its second stage. The punchings from the pieces 21 are formed in and fall downwardly through shear perforations 17, and the punched out pieces 21 fall through shear perforation 18 into a collecting chute or tube 19. In this case, the latter is shown with a displaceable bottom 20 that comprises a magnetized disc held by its magnetism against the open bottom end of chute or tube 19. Should tube 19 become filled with pieces 21 before the same can be emptied, the magnetic bottom 20 will be forced away from tube 19 by the pressure on the stack of pieces in said tube, as created by the punch that shears out said pieces. Normally, however, when a suitable quantity of pieces has been produced, the same are removed after manual displacement of bottom 20.

The punch 14 comprises a metal block 22 which, in its first stage, mounts a set of metal punch elements 23 aligned with and adapted to enter shear perforations 17 after having first sheared through work strip 15. These punch elements, of course, conform in size and shape to the respective perforations 17. Said elements 23 are provided as inserts that are readily replaced if damaged or broken. Thus, each element 23 is formed to have a shank 24 tightly yet removably engaged in block 22. At its second stage, block 22 carries a punch element 25 that similarly coacts with shear perforation 18 to punch pieces 21 from strip 15.

A conventional stripper plate 26 is carried by punch block 22 and is resiliently pressed by spring means 27 to hold work strip 15 down against die block 16 during the time that the punch elements are being projected and retracted into and out of their respective perforations. A stud or tongue 28 on the punch block 22, in the usual manner, constitutes the means effecting connection of punch 14 to ram 7.

The foregoing is generally conventional for progressive die sets that punch out perforated pieces from a work strip. It will be understood that the stage embodying perforation 18 and punch element 25 may be omitted if only a perforated work strip is to be produced or said stage may be provided in compound or double-acting association with the perforations 17 and punch elements 23.

According to the present invention, means is provided

for stopping the operation of the press upon an abnormal condition in the die set 12, as when one or more of the punch elements 23 are broken or improperly inserted in the punch 14. In this disclosure, the press is stopped by opening the electric circuit to motor 10. The press may be stopped in other ways as by locking the one-revolution clutch open so that there is no drive to shaft 9, or by simultaneously setting a brake on the crank 8 or flywheel 11 when the motor circuit is opened.

The present novel means comprises three interconnected electric circuits from a line or current source 29, 30. One circuit 31 controls motor 10; the second circuit 32 is closed when ram 7 is retracted and open when said ram is projected and controls circuit 31; and the third circuit 33 is open when the ram is retracted and closed when the ram is projected and also controls motor circuit 31. Either circuit 32 or 33, when closed, will close the motor circuit. If both circuits 32 and 33 are open at the same time, the motor circuit will also be open and the press cannot operate.

Circuit 31 is shown as comprising a bridging plate 34 for a pair of terminals 35 and 36, a connection 37 from terminal 35 to one pole of motor 10, a connection 38 from terminal 36 to line conductor 29, and a connection 39 between the other pole of the motor and line conductor 30. It will be clear that when plate 34 is in bridging contact with terminals 35 and 36, motor 10 is in circuit with the current source.

Circuit 32 includes a solenoid 40 on the floating 41 core on which is carried bridging plate 34, and also includes a switch 42 that is mounted on press frame 5 in operative association with an adjustable actuator screw 43 carried by ram 7. Said solenoid and switch are arranged in a series circuit with line 29, 30, of which circuit a connection 44 extends between line conductor 29 and switch 42, a connection 45 extends between said switch and said solenoid, and a connection 46 extends between said solenoid and line conductor 30. From the foregoing, it will be seen that when ram 7 is retracted, solenoid 40 is energized by circuit 32, because switch 42 is normally closed, to cause projection of plate 34 into bridging contact with terminals 35 and 36 to, thereby, close motor circuit 31, and that when the ram moves toward its projected position, near the end of such movement, actuator 43 engages button 47 of switch 42 to open the latter and circuit 32. Since said solenoid is now de-energized, gravity or suitable spring means retracts core 41 and moves plate 34 to open the motor circuit 31.

Circuit 33 includes the mentioned solenoid and circuit-closing means 48 provided in die set 12.

The means 48 includes the mentioned punch elements 23 and a set of metallic die elements 49 carried by block 16, two terminals 50 and 51 connected to the latter elements, and metal pieces 52 that electrically connect the upper ends of shanks 24 of the punch elements in pairs. Said punch elements 23 and pieces 52 are electrically insulated from block 22 by being set in a solid and strong insulating block 53 of phenolic resin or phenolic resin-impregnated cloth or paper. In any case, the punch elements are arranged as electrically connected pairs which can only be connected in series circuit when entered into and engaging die elements 49. Stripper plate 26, if one is used in the die set, is preferably made of an insulating material similar to block 53, or at least so made as not to short the pairs of punch elements. The set of die elements 49, in a similar manner, is insulated from die block 16 by an insulating block 54 in which said die elements are set. Said set of die elements 49 comprises single-perforation blocks 55 and 56 and one or more intermediate two-perforation blocks 57. The number of the latter blocks depends on the number of pairs of punch elements provided in the punch 14. The shear perforations 17 are provided in said set of die blocks. Terminal 50 is connected to block 55 and terminal 51 to block 56. By this arrangement, when the punch elements are entered in

perforations 17, a series electric circuit is closed between terminals 50 and 51.

The arrangement may be reversed with the die blocks arranged in pairs and the end punches of a set of punch elements provided with terminals 50 and 51.

It will be seen from the foregoing that punch elements 23, after shearing through work strip 15, enter perforations 17 and make electrical contact with the die blocks 49 and that a series circuit, starting with terminal 50 and following the path shown by the dotted arrows to terminal 51. It will be clear that the means 48 constitutes a switch in circuit 33 since said circuit is open when the punch elements are elevated or retracted from the die elements. It will also be seen that the circuit shown by said dotted arrows becomes interrupted should one or more of the punch elements be broken or should one or more of said elements be improperly seated and out of contact with one or more of the pieces 52. Thus, upon such an abnormal condition in the die set, circuit 33 will not close. Should there be an odd number of punch elements 23 in the punch, a dummy element may be provided and placed outside the periphery of the piece to be punched out and even outside the path of strip 15.

A connector 58 connects terminal 50 with connector 45 and solenoid 40, and a connector 59 connects line conductor 29 and terminal 51. In this manner, switch 42 and the die circuit 48 are connected in parallel, said switch holding the motor circuit 31 until die circuit 48 is closed, at which time actuator 43 opens said switch and the motor circuit is held closed by said die circuit.

If conditions are normal, the press will operate to successively produce pieces 21 since each projection of the ram causes open circuit 33 to close as closed circuit 32 opens, and each retractive movement of said ram causes closed circuit 33 to open and open circuit 32 to close. The motor circuit 31, therefore, remains closed at all times. However, under one or the other abnormal conditions mentioned, circuit 33 will remain open after circuit 32 is opened by actuator 43. Since there is no current in solenoid 40, the same becomes de-energized and plate 34 leaves contact with terminals 35 and 36 to open motor circuit 31. Therefore, the motor will stop.

It will be realized that the work strip 15 must be of non-conducting material otherwise the die circuit will not be operative as above described.

While I have described what I now regard as the preferred form of my invention and being aware that modifications thereof may be made, I desire to reserve to myself such modifications and variations of my invention that may fall within the spirit and scope of the appended claims.

Having thus described my invention, what I claim and desire to obtain by Letters Patent, is:

1. The combination with a press having a bed and a ram and provided with means to reciprocate the ram relative to the bed and with a driver for said means: of a die unit affixed to the bed and provided with metallic blocks having shear perforations, said blocks being insulated from each other and from the die unit; a punch unit carried by the ram and provided with metallic punch elements arranged to enter said shear perforations after piercing through a non-metallic work piece interposed between the die and punch units, said punch elements being insulated from the punch unit; means electrically connecting said punch elements in pairs; said punch elements, when entered in the mentioned die blocks, and said element-connecting means combining to form a series electric switch circuit; a current source for said switch circuit; a parallel electric circuit across the switch circuit and including a normally-closed switch; means carried by the ram to open said switch after said punch elements enter said perforations; an electric circuit for the driver of the ram; and a control for the driver circuit by said parallel circuits comprising electrical connections between

said parallel circuits and the driver circuit including a solenoid-controlled switch in the latter circuit.

2. The combination according to claim 1: a solenoid in series with said parallel electric circuits and energized only when one or the other of said parallel circuits is closed; said solenoid-controlled switch being arranged to be closed only when the solenoid is energized.
